ELECTRICAL INSTRUMENT HOUSING

John Gugliotta, Elizabeth, and Gerald Stolar, Linden, N.J., assignors to Daystrom, Incorporated, Murray Hill, N.J., a corporation of New Jersey

Application May 15, 1958, Serial No. 50,903

Term of patent 14 years

(Cl. D52—1)

Figure 1 is a front view of an electrical instrument housing showing our new design;

Figure 2 is a side view thereof; and

Figure 3 is a cross-sectional view of the face portion taken along the line 3—3 of Figure 1, and drawn to an enlarged scale.

We claim:

The ornamental design for an electrical instrument housing, substantially as shown.
